ADOLF FRANKE, OF GRUNEWALD, AND ERWIN EHRHARDT, OF PANKOW, GERMANY,
ASSIGNORS TO SIEMENS & HALSKE AKTIENGESELLSCHAFT, A CORPORATION OF
GERMANY.

TELEGRAPHIC TYPE-PRINTING RECEIVER.

1,177,694.

Specification of Letters Patent.

Patented Apr. 4, 1916.

Application filed August 19, 1911. Serial No. 644,901.

To all whom it may concern:

Be it known that we, ADOLF FRANKE and ERWIN EHRHARDT, subjects of the German Emperor, and residing, respectively, at 5 Grunewald and Pankow, near Berlin, Germany, have invented certain new and useful Improvements in Telegraphic Type-Printing Receivers, of which the following is a specification.

10 Our invention relates to telegraphic type-printing receivers, in which the symbol to be printed is not formed by one single current impulse corresponding to one character, but by a combination of a plurality of impulses following one another in succession, and in which the device for distributing the arriving impulses and the type-wheel for printing the symbols are synchronously driven by one shaft. Means for operating a 15 shaft synchronously with arriving electrical impulses are known in the art. They are for instance disclosed in the U. S. Patent No. 690,248 of December 31, 1901, to William Duane, and also in the British Patent No. 21304/1903 to Siemens Bros. The illustration and description of such means has 20 therefore been omitted in the present description, so as not to unnecessarily complicate the disclosure of the principal subject 25 matter of the present invention. In the following description it may be assumed that the shaft W which controls the operation of the distributing elements is operated synchronously with the arriving impulses in 30 a suitable manner, such as shown in the aforesaid patents. In type-printing receivers of this character known heretofore two successive operations are in general to be distinguished namely the receiving and storing 35 of the arriving symbols, and the subsequent translation proper of the symbols into typed characters. During the translation of a symbol a new symbol cannot be received by the receiving apparatus. For this reason, in 40 such apparatus the line either remains partially unused, or a plurality of receivers which alternately operate for receiving and translating are connected to the same line.

Now a primary object of our invention is

to utilize the line completely when employing only one symbol receiving apparatus. We attain this end by combining with the receiving apparatus a translating device which receives the impulse serving for translating a symbol and simultaneously translates a previously received symbol by means of a type-printing device.

In order to be able to receive a new symbol with the receiving apparatus while the previously received symbol is being translated, a translating device is provided according to the present invention, which comprises two or more groups of polarized relays. These groups of relays are alternately connected by means of change-over switches with the receiving device for the impulses and with the translating device. By these means the group of relays connected with the receiving device is always controlled by the arriving impulses, that is to say, it is used for receiving the arriving symbols, while simultaneously the other group which is connected with the printing device, translates the previously received symbols. The number of controlling means, respectively relays, 75 united into one group, depends of course entirely upon the number of impulses of which the symbols are composed.

In the accompanying drawing, the invention which has been reduced to practice is 80 shown in more or less diagrammatical form in which the translating device consists of two groups of polarized relays, R₁, R₂ and R₃, R₄. For a clearer understanding of the invention it is assumed here that each symbol sent over the line L consists only of two impulses which are distinguished only by the direction of current, so that according to whether two positive or two negative, or one positive and one negative impulse is 85 sent, four different symbols can be transmitted. In compliance with this assumption the stationary receiving ring S₁ of the receiver has only two segments r, s, on which the brush a slides, which is directly connected with the line L, and which rotates synchronously with the transmitter in a manner referred to in the abovementioned patents.

The segments r , s , are connected by way of change-over switches, u_1 , u_2 , either with the two relays R_1 , R_2 of one group, or R_3 , R_4 of the other group. Switches u_1 , u_2 are operated by means of connecting bar g . This bar is controlled by a spring f in one direction and by a cam k , mounted on shaft i in the other direction. This latter control is obtained by a rocking lever m pivoted at one 10 end to bar g and resting with its other end against cam k through the action of spring f . Thus when the elevated cam surface strikes lever m , switches u_1 — u_4 move into a position shown in dotted lines. This changing of 15 switch position takes place after each complete revolution of the brush arm x , at the moment its brush a glides over the insulated portion n of slip ring s_1 . Accordingly switches u_1 , u_2 are alternately in the left 20 hand and right hand position during succeeding revolutions of shaft W . The particular arrangement by which the switches u_1 — u_4 are shifted is immaterial for the present invention, so long as the operation 25 takes place in proper timed relation to the remaining elements of the device, and while we have illustrated a possible way in which this can be accomplished in order to show a complete operating device, we do not claim 30 the particular construction shown as new.

In the position in which the apparatus is shown in the drawings, segment ring r is connected with relay R_1 by way of switch u_1 , whereas segment ring s is connected with 35 relay R_2 by switch u_2 of the same group. The current impulses arriving over the line A and returning to ground E energize successively, during one revolution of brush arm x , the relays R_1 , R_2 , so that their respective armatures a_1 , a_2 are attracted either in 40 one or in the other direction. Since after a complete revolution of arm x switches u_1 , u_2 are shifted into their other position, relays R_3 , R_4 are connected with slip rings r , s instead of relays R_1 , R_2 and accordingly the 45 impulses arriving during the next revolution of the receiver control and operate armatures a_3 , a_4 . After the completed revolution the switches u_1 , u_2 are thrown over and the 50 cycle of operations commences anew. Simultaneously with the aforementioned adjustment of the relays by the arriving impulses the printing or translation of the symbol previously received takes place by 55 the properly energized relays; in other words, while one group of the relays is connected with the receiving ring S_1 of the receiver, the armatures of the other group of relays are thrown into circuit with a local 60 battery, which circuit also contains the printing electromagnet D . This electromagnet D attracts its armature d and thereby throws the paper strip p fed by drum q against the type wheel y arranged on shaft W , so that

the printing of the type which happens to be 65 in the printing position takes place. For this purpose change-over switches u_3 , u_4 are provided which simultaneously with switches u_1 , u_2 are operated by bar g .

The device for reproducing the symbols 70 consists according to the present disclosure, essentially of the two additional stationary segment rings S_2 , S_3 , printing magnet D , the two mentioned change-over switches u_3 , u_4 , and the relay armatures a_1 , a_2 or a_3 , a_4 each 75 of which operating when desired. All of the elements operating simultaneously are disposed in series arrangement with the battery circuit so that the operation of the printing magnet depends upon the bridging of all 80 contacts located in series.

The translation of the symbols takes place 85 as follows: In the position shown in the drawings, as has been mentioned already the two relays R_1 , R_2 are electrically connected with ring S_1 and they receive successively the impulses arriving over line L , whereby the relays are connected to the ground at one pole as shown. On the other hand, relay armatures a_3 , a_4 and their respective contacts 90 are connected with the printing magnet D by way of switches u_3 , u_4 , with battery B in circuit, the whole circuit arrangement being such that it is only necessary to bridge two 95 segments on the segment rings S_2 , S_3 in order to energize the printing magnet and to effect the printing of the symbol in type. This bridging however can occur in the position of the relay armatures only at a definite moment which is characteristic for the special 100 type character, in so far as it determines the angle of rotation of type wheel y and thus the placing of the type in printing position. In the position of the elements shown armatures a_3 , a_4 of relays R_3 , R_4 are in contact 105 with the left hand contacts. As can be seen from the diagram these latter contacts are connected with segment v of ring S_3 and also with segment z of ring S_2 . On these two rings glide two brushes b_2 , b_3 which are electrically connected with each other and which are also mounted on arm x . Therefore a connection of both relay contacts can take 110 place only when segments z and v are simultaneously in contact with their respective brushes b_2 , b_3 , which is the case only during the last quarter of the revolution of brush arm x and shaft W . When connection is thus made a current can flow from battery B through electromagnet D , switch u_3 , armature a_4 of relay R_4 , segment z , brushes b_2 , b_3 , segment v , armature a_3 of relay R_3 , and switch u_4 back to the battery B . The printing magnet attracts its armature d and thereby throws the paper strip p which is located 115 between the other end of the armature and the type wheel y , against the character which is then presented to the strip. At the com-

pletion of the revolution of the brushes on the segment disk, also the reversion of switches u_3, u_4 takes place as has been already mentioned, by which now instead of the 5 armature contacts a_3, a_4 of relay group R_3, R_4 , now armature contacts a_1, a_2 of relay group R_1, R_2 are thrown in circuit with printing magnet D. Thus during the next 10 revolution of brush arm α the symbol is translated which corresponds with the armature position of this relay group.

In the practical apparatus it is of course advisable owing to the large number of symbols necessary for transmitting speech, and 15 for the reliable transmission of the signals to use not only two impulses for characterizing a symbol, but more, for instance 5 and in this case these impulses are not only distinguished by their character (whether 20 negative or positive) but also by their timely arrival. Within which time an impulse arrives is immaterial, for the present invention. On the other hand, it is essential that within one given time interval during which 25 a symbol arrives, also the translation of the previously received impulse into printed type is effected by means of only one receiving apparatus.

We claim:—

30 1. In a printing telegraph receiver, a main line, means for receiving and distributing current impulses arriving over said line, a printing mechanism and a working circuit therefor, in combination with a changing over device operated synchronously with said current impulses, and a plurality of groups of adjusting devices and suitable circuit connections therefor and means whereby the single groups of said devices alternatively set the working circuit for said printing mechanism and close the circuit previously set by another group.

2. In a printing telegraph receiver, a main line, means for receiving and distributing 45 current impulses arriving over said line, comprising a fixed and a rotatable element, a printing mechanism and a working circuit therefor in combination with a changing over device, a shaft operated synchronously with said current impulses for operating the rotatable element of said receiving means, and a plurality of groups of adjusting devices and suitable circuit connections therefor and means whereby the single groups of 50 said devices alternatively set the working circuit for said printing mechanism and close the circuit previously set by another group.

3. In a printing telegraph receiver, a main 60 line, means for receiving and distributing current impulses arriving over said line, a type wheel, a printing magnet coöperating therewith, a working circuit for said magnet, and a selector consisting of a fixed and

a rotatable element, in combination with a 65 changing over device, a shaft driven synchronously with said current impulses for driving said type-wheel and the rotatable element of said selector, and a plurality of groups of adjusting devices and appertaining 70 circuits therefor and means whereby the single groups of said devices alternatively set the working circuit for said printing magnet and close the circuit previously set by another group. 75

4. In a printing telegraph receiver, a main line, means for receiving and distributing current impulses arriving over said line and a printing mechanism having a suitable working circuit for operating it, in combination with a changing over device, means for causing it to operate synchronously with said current impulses, and a plurality of groups of relays with their operating armatures, the armatures of the single groups of 80 said relays having suitable circuit connection and means for alternatively setting the working circuit for said printing mechanism and for closing the circuit previously set by another group. 90

5. In a printing telegraph receiver, a main line, means for receiving and distributing current impulses comprising a fixed and a rotatable element, a type wheel, a printing magnet coöperating therewith and a suitable 95 working circuit for actuating said magnet, and a selector consisting of a fixed and a rotatable element in combination with two groups of relays with their appertaining armatures and of switches and appertaining 100 circuits therefor the one group of said switches being connected to the fixed element of said receiving means and adapted to control the circuits of said relays, the other group being connected in circuit with said 105 printing magnet, said relay armatures constituting switches having their contact points connected in circuit with the fixed element of said selector, said armatures being connected in circuit with said second 110 group of switches which is in circuit with said printing magnet.

6. In a printing telegraph receiver, a main line, means for receiving and distributing current impulses arriving over said line comprising a fixed and a rotatable element, a type-wheel, a printing magnet coöperating therewith and a suitable working circuit for actuating said magnet, and a selector consisting of a fixed and a rotatable element, in 115 combination with two groups of relays with their appertaining armatures and of switches and appertaining circuits therefor, the one group of said switches being connected to the fixed element of said receiving 120 means and adapted to control the circuits of said relays, the other group being connected in circuit with said printing magnet, 125

said relay armatures constituting switches, having their contact points connected in circuit with the fixed element of said selector, said armatures being connected in circuit with said second group of switches which is in circuit with said printing magnet, and a shaft rotating synchronously with said current impulses for driving the moving elements of said receiving means and of said

selector and for operating said type-wheel 13 and said switches.

In witness whereof, we hereunto subscribe our names.

ADOLF FRANKE.
ERWIN EHRHARDT.
